UNITED STATES PATENT OFFICE.

JAMES J. HENNESSY, OF NEW YORK, N. Y.

LUBRICATOR FOR LOCOMOTIVE JOURNALS.

1,412,741.

Specification of Letters Patent. Patented Apr. 11, 1922.

Application filed July 19, 1920. Serial No. 397,342.

To all whom it may concern:

Be it known that I, JAMES J. HENNESSY, a citizen of the United States, residing at New York city, New York, have invented 5 a certain new and useful Improvement in Lubricators for Locomotive Journals, of which the following is a full, clear, and exact description, such as will enable others skilled in the art to which it appertains to make and 10 use the same, reference being had to the accompanying drawings, forming part of this specification.

My invention relates generally to automatically operating lubricating devices, and 15 more particularly to a locomotive journal lubricator of the general type disclosed in my copending applications, Serial Number 250,045, filed August 15, 1918, and Serial Number 352,098, filed January 17, 1920. 20 The principal objects of my present invention are to generally improve upon and simplify the construction of the lubricating devices disclosed in the applications aforesaid, and to provide a relatively simple lubricating device that is wholly automatic in 25 operation, positive in its action of circulating the liquid lubricant, and effective to a high degree in performing its intended functions.

30 Further objects of my invention are, to provide an automatic lubricator for locomotive journals that, by virtue of its relatively simple construction, may be easily and cheaply produced; to provide a construction 35 wherein the pumping apparatus or movable parts which effect a circulation of the liquid lubricant are separate from the housing and relatively stationary parts of the lubricator, thereby permitting said operating parts to 40 be readily removed for inspection, adjustment or repair; to provide a construction wherein the plunger actuating rod is self-adjusting and constructed so that it will yield longitudinally under abnormal lateral move-

45 ment of the wheel part that imparts movement to it, thereby eliminating the liability of any part of the pumping mechanism becoming broken as a result of such abnormal movement; to provide a lubricator wherein 50 the liquid lubricant is delivered to the waste in the waste receptacle at such a height as to eliminate the necessity for having an oil tight connection between the pump and said waste receptacle; and, further, to construct 55 the lubricator parts so as to entirely eliminate the requirement for packing strips or

closely fitting parts to prevent the oil from splashing out of its container.

With the foregoing and other objects in view, my invention consists in certain novel 60 features of construction and arrangement of parts hereinafter more fully described and claimed, and illustrated in the accompanying drawings, in which—

Figure 1 is an elevational view of a lubricating device of my improved construction, with dotted lines showing part of a locomotive axle and wheel with which the lubricator is associated.

Figure 2 is an end elevational view of my 70 improved lubricator and showing in section the journal with which the device is associated.

Figure 2^a is a detail section taken approximately on the line 2^a—2^a of Figure 2.

Figure 3 is an enlarged cross section taken approximately on the line 3—3 of Figure 1.

Figure 4 is a vertical section taken lengthwise through the center of the lubricator and approximately on the line 4—4 of Figure 3.

Figure 5 is a plan view of the lubricator with parts thereof broken away.

Figure 6 is an enlarged section taken approximately on the line 6—6 of Figure 5.

Figure 7 is a cross section taken approximately on the line 7—7 of Figure 6.

Figure 8 is a detail section of the self-adjusting push rod that is utilized for actuating the plunger of the liquid lubricant pump.

Figure 9 is a perspective view of a sleeve 90 that forms a part of the self-adjusting push rod.

Figure 10 is a perspective view of a bell crank that is utilized for transmitting the 95 motion of the push rod to the pump plunger.

Figure 11 is a perspective view of a spring-held detent that is utilized in the self-adjusting push rod.

Figure 12 is an enlarged cross section taken approximately on the line 12—12 of Figure 7.

Referring by numerals to the accompanying drawings, which illustrate a practical embodiment of my invention, 10 designates the main body of the lubricating device, the same being preferably constructed of cast metal and in the form of an open topped receptacle, the side walls of which 110 extend a substantial distance above the end walls. This construction enables the hous-

ing to partially enclose the lower portion of the journal to which it is applied and the underside of the body 10 is provided with perforated lugs, by means of which it may be rigidly secured to adjacent parts of the locomotive frame.

Formed integral with one end of the body 10 is a depending casing 11, the chamber 12 within which serves as a well for containing the supply of liquid lubricant that is circulated through the device. That portion of the casing 11 that projects beyond the adjacent end wall of the body 10 is provided with a removable cover plate 11^a which permits the well or chamber 12 to be refilled with liquid lubricant from time to time.

The upper surface of the bottom of the body 10 gradually declines toward the well or chamber 12 so that all liquid lubricant 20 passing onto said bottom will drain into said well. Removably positioned within receptacle 10 is a relatively shallow pan 13, preferably constructed of cast metal, and the upper edges 14 of its end walls are 25 formed on arcs of circles that have the same radius as the journal with which the lubricator is associated, and the inner end wall of this pan overlies the corresponding end wall of the contained body 10. The 30 pan 13 is yieldingly supported upon the inclined bottom of the container body 10 by means of compression springs 15 and formed integral with the underside of that portion of the pan that is positioned adjacent to the hub of the axle with which the device is associated is an elongated cylindrical block 16 in which is formed a horizontally disposed bore 17. Arranged for 35 sliding movement in this bore is a cylindrical member 18 which forms a part of the plunger push rod, and secured in any suitable manner to the outer end of this cylindrical member 18 is a plate 19, the outer face of which is adapted to contact directly 40 with the adjacent face of the locomotive wheel hub or a part carried thereby.

Formed integral with the upper edge of the plate 19 is a horizontally disposed flange 20 that occupies a position directly 50 beneath an outwardly projecting flange 13^a that is formed on the adjacent end wall of the pan 13. (See Figs. 2 and 6.)

In order to maintain this plate in proper 55 position and resist any tendency of the same to rotate while in contact with the wheel hub, one end of said plate carries a pin 21 which enters a bore or passageway 22 that is formed in the corresponding corner of the pan 13. (See Fig. 2^a.)

Secured in any suitable manner to the 60 underside of the bottom of the pan 13 and adjacent to the outer end thereof is a depending block 23, the same projecting downwardly into well 12 and formed in 65 said block is a pumping chamber 24 and

a liquid lubricant passageway 25 the lower ends thereof being connected by a port 26. This port 26 is normally closed by a spring-held valve 27 which is seated so as to admit liquid lubricant from chamber 24 into chamber 25 and the upper end of the latter chamber communicates with an opening 28 that is formed in the bottom of pan 13.

Formed through the lower portion of the wall of the block and communicating with the plunger chamber 24 is a liquid lubricant inlet port 29. Arranged for reciprocating movement in chamber 24 is a cylindrical pump plunger 30 and formed through the upper portion thereof is a transversely disposed aperture 31.

Connected in any suitable manner to cylindrical member 18 is a horizontally disposed push rod 32 and the end thereof is arranged for sliding movement in suitable 85 bearings formed through the top of block 23. A portion of this rod 32 between the blocks 16 and 23 is provided with a series of annular grooves 33 that are substantially V-shape and the ribs between these grooves 90 are substantially of inverted V-shape in cross section.

Loosely arranged on the rod 32 between the blocks 16 and 23 is a sleeve 34, one end of which is reduced in diameter to provide a 95 shoulder 35 against which bears one end of a compression spring 36, the other end of the latter bearing against the block 23. (See Figs. 6 and 8.) Formed in the body of sleeve 34 and on opposite sides thereof are 100 notches 37 that are occupied by the upper ends of the relatively short vertically disposed legs of a bell crank 38 that is fulcrumed upon a pin 39 and the latter being seated in ears 40 that are fixed to and project downwardly from the bottom of pan 13.

The free end of the relatively long horizontally disposed arm 41 of the bell crank 38 extends through a vertically disposed slot 42 that is formed in the upper portion of block 23 and the end of said arm is positioned in the transverse slot 31 that is formed in the upper portion of plunger 30. Thus the member 18, rod 32, and sleeve 34 constitute a push rod which, during operation, is moved lengthwise by the wheel hub as the latter moves laterally with respect to the lubricating device and as the push rod is thus actuated, bell crank 38 will be swung upon its fulcrum to move plunger 30 downwardly in chamber 24 and upon the movement of the wheel hub away from the lubricating device, the spring 36 will turn the push rod, bell crank, and plunger 30 to their normal positions. In order to render this 120 push rod self-adjusting and to permit it to yield under abnormal lengthwise movement and thus prevent the breakage of some parts of the pumping mechanism, I arrange spring-pressed clutches or detents on the 125 130

sleeve 34, said clutches or detents being in the form of small plugs 43 that are provided on their inner ends with V-shaped teeth 44, and the latter being adapted to engage in 5 the grooves 33, that are formed in rod 32. These plugs 43 are arranged for sliding movement in apertures 45 that are formed in sleeve 34, and said plugs are carried upon the central portions of relatively light 10 springs 46 and which latter occupy longitudinally disposed grooves 47 that are formed in the sleeve 34. One end of each of these springs is secured to sleeve 34 in any suitable manner, and under normal or ordinary 15 working conditions, the engagement of the teeth 44 on the inner ends of said plugs in one of the grooves 33 serves to lock the sleeve 34 to push rod 32, but in the event of abnormal longitudinal movement of the 20 push rod, the excessive pressure upon the latter will force the plugs 43 outwardly a sufficient distance to disengage the teeth 44 from the rod 32, thereby enabling the latter to move independently of the sleeve 34. 25 Further, this particular construction permits my improved lubricator to be applied to a journal that has an abnormal amount of lateral movement during operation without cutting off any part of the push rod or constructing the same to any definite length, 30 for when the lubricator is applied to the journal box, the contact plate 19 that is carried by the inner end of the push rod is pulled out far enough to make contact with 35 the face of the wheel hub when the latter is at its limit of movement away from the inner end of the lubricator and following the first movement of the wheel hub toward the lubricator, push rod will be forced 40 through sleeve 34 past the clutches or detents 43 and thereafter the device will continue to operate and function in the desired and proper manner.

I have demonstrated in practice that satisfactory results can be obtained and sufficient movement imparted to plunger 30 by a quarter inch longitudinal movement of the 45 push rod.

Formed integral with the bottom of the 50 pan 13 and projecting upwardly therefrom are ribs or lugs 48 and resting upon the latter is a thin plate 49, preferably of sheet metal, which serves as a support for fibrous material such as waste and which latter is 55 adapted to make direct contact with the journal for the purpose of delivering liquid lubricant to the surface thereof. Formed in the center of this plate 49 is an aperture 50 and secured to said plate around said aperture is a short upwardly projecting tube 51. This tube extends upwardly into and through the body of waste positioned on the plate 49 and the greater portion of the oil that is pumped upwardly into the pan 13 60 will be forced upwardly through this open

tube 51 and thus be freely delivered directly to the upper portion of the body of the waste near its central point. The perforations in plate 49 will permit the passage of oil therethrough but the waste packed above 70 same will restrict the amount of oil supplied to the journal in this manner, leaving tube 51 to function as described.

When my improved lubricator is properly installed for use, it will be understood that 75 sufficient waste is placed upon plate 49 in pan 13 to make direct contact with the underside of the journal and that a sufficient supply of liquid lubricant is placed in well 12. The axle having the journal to which 80 the device is applied always has a certain amount of lateral movement during operation and as the wheel adjacent to the device moves toward the same, the face of the wheel hub will bear against the outer face of plate 85 19, thereby moving the same and the push rod a slight distance (approximately a quarter of an inch) lengthwise through the device. As a result of this movement of the push rod, bell crank 38 will be actuated to 90 move plunger 30 downward in chamber 24, and as the lower end of said plunger passes inlet port 29, a portion of the oil trapped in the chamber below said plunger will be forced past check valve 27 into the outlet 95 passageway 25 and as the latter is filled with liquid lubricant, a corresponding amount of the latter will be forced through the opening 28 in pan 13. As the wheel hub recedes or moves away from plate 19, compression 100 spring 36 will return the parts of the pumping mechanism to their normal positions and the operations just described will be repeated as the wheel hub again moves toward the lubricator. As a result of these continued 105 operations, small quantities of oil are intermittently discharged through opening 28 into the pan 13 and this oil will in turn be forced upwardly through tube 51 into the center of the body of waste positioned on 110 plate 49 and thus keeping said body of waste saturated at a central point adjacent the journal to be lubricated, and consequently effecting a thorough lubrication of the latter.

The supply of liquid lubricant is contained in a well that is practically closed at its top so that it is impossible for the supply of oil in the well to splash upwardly and escape from the lubricator and any oil which may escape between the inner portion of the journal and the flange 13^a will pass downwardly onto flange 20 at the top of plate 19 and after passing thereover will discharge back into the lower portion of the container 10.

The pan 13 and parts associated therewith are yieldingly supported within the container 10 and likewise yieldingly mounted in position against the underside of the journal by the springs 15 and for the purposes 130

of repair, inspection or adjustments, all parts of the pumping mechanism are connected to the pan 13 and the latter is arranged so that it can be readily lifted from the container body 10.

A lubricating device of my improved construction is comparatively simple, can be easily and cheaply produced, is applicable for use in connection with practically all existing types of locomotive journal boxes, is wholly automatic in operation, and is very effective in pumping liquid lubricant to the waste or like material which makes direct contact with the journal of the axle, thereby insuring constant lubrication of that portion of the journal that engages the brass or journal bearing.

It will be readily understood that minor changes in the size, form and construction of the various parts of my improved lubricating device can be made and substituted for those herein shown and described, without departing from the spirit of my invention, the scope of which is set forth in the appended claims.

I claim as my invention:

1. In a journal lubricator, a container, a receptacle positioned in said container, pumping means carried by said receptacle and adapted to be actuated by the lateral movement of the journal with which the lubricator is associated for effecting a circulation of liquid lubricant from the container to the receptacle, and which receptacle and pumping means are bodily removable from said container.

2. In a journal lubricator, a container, a receptacle positioned in said container, pumping means carried by said receptacle and adapted to pump liquid lubricant from the container into said receptacle, said pumping means having a part that is adapted to be actuated by the lateral movement of the journal with which the lubricator is associated, and a waste supporting plate within said receptacle.

3. In a journal lubricator, a container, a receptacle positioned in said container, pumping means carried by said receptacle and adapted to pump liquid lubricant from the container into said receptacle, said pumping means having a part that is adapted to be actuated by the lateral movement of the journal with which the lubricator is associated, and a waste supporting plate within said receptacle, said receptacle, pumping means, and waste supporting plate being bodily removable from said container.

4. In a journal lubricator, a container provided with a liquid lubricant well, a receptacle positioned in said container, a pump having a part extending downwardly into the well of the container, a push rod for operating said pump, which push rod is adapt-

ed to be actuated by the lateral movement of a part of the journal with which the lubricator is associated, and a waste supporting plate positioned in said receptacle, which receptacle, pumping means, and waste supporting plate are bodily removable from said container.

5. In a journal lubricator, a container provided with a liquid lubricant well, a receptacle positioned in said container, a pump carried by said receptacle and having a part depending into the well, and a pump actuating push rod carried by said receptacle, which push rod includes a spring-held sleeve that is yieldingly connected to said rod.

6. In a journal lubricator, a liquid lubricant pump including a cylinder provided with a plunger, a lubricant supply passage fed by said plunger, a bell crank connected to said plunger and adapted to actuate the same, a push rod, and a spring-pressed member yieldingly connected to said push rod and which member is connected to said bell crank.

7. In a journal lubricator, a container provided with a liquid lubricant well, a receptacle yieldingly supported in said container, a pump carried by said receptacle and having a portion depending into the liquid lubricant well, a push rod, operating connections between said push rod and a part of the pump, and a plate carried by said push rod and adapted to be engaged by a part carried by the axle with which the lubricator is associated.

8. In a journal lubricator, a container provided with a liquid lubricant well, a receptacle positioned in said container, a pump carried by said receptacle for delivering liquid lubricant from the well into said receptacle, a spring-held push rod carried by the receptacle and having operating connections with said pump, and means associated with said push rod for automatically adjusting the length of the stroke transmitted to the pump.

9. In a journal lubricator, a receptacle, a waste supporting plate positioned in said receptacle, and a tube projecting upwardly from said plate into the body of waste positioned thereupon.

10. In a journal lubricator, a receptacle, a plate positioned therein and maintained in a plane above the bottom thereof, which plate is adapted to support waste, and a tubular member projecting upwardly from said plate into the body of waste positioned thereupon.

11. In a journal lubricator, a receptacle, a plate positioned therein and maintained in a plane above the bottom thereof, which plate is adapted to support waste, a tubular member projecting upwardly from said plate into the body of waste positioned

thereupon, and means for delivering liquid lubricant into the space between said plate and the bottom of the receptacle.

12. In a journal lubricator, a lubricant reservoir, a receptacle above same adapted to be packed with waste, a passage from said reservoir to the bottom of said receptacle, and a tube leading through the bottom of said receptacle to a point adjacent the upper face of any waste packed in said receptacle.

13. In a journal lubricator, a lubricant reservoir, a receptacle above same adapted to be packed with waste, a passage from said reservoir to the bottom of said receptacle, and a tube positioned centrally of said receptacle and leading through the bottom thereof to a point adjacent the surface of a journal to be lubricated.

14. In a journal lubricator, a pump, a pump rod extending through the lubricator wall and adapted to be engaged by an external element to operate said pump, and a pump and rod connection member adapted

to automatically accommodate varying relative positions of the pump and the external element.

15. In a journal lubricator, a lubricant reservoir, a pump extending into same, a pump operating rod slidably mounted at its opposite ends, a connection between said pump and rod slidably mounted upon said rod, and yielding means for positioning said connection upon said rod.

16. In a journal lubricator, a lubricant container, a lubricant applying receptacle above said container, parallel vertical passages connected to said container and receptacle respectively at opposite ends and connected to each other at one end, and a plunger adapted to be reciprocated in one of said passages by relative movements of the lubricator and the journal to which it is applied.

In testimony whereof I hereunto affix my signature this ninth day of July, 1920.

JAS. J. HENNESSY.
